UNITED STATES PATENT OFFICE.

LOREN L. WHITNEY, OF HAMMOND, INDIANA, ASSIGNOR TO AMERICAN STEEL
FOUNDRIES, OF CHICAGO, ILLINOIS, A CORPORATION OF NEW JERSEY.

METHOD OF MAKING BRAKE-BEAM FULCRUMS.

Application filed October 23, 1924. Serial No. 745,313.

This invention relates to a method of making a brake beam fulcrum.

One object of the invention is to provide a simple, efficient and inexpensive method of 5 making a brake beam fulcrum.

Another object is to provide a method of making a brake beam fulcrum consisting in a minimum number of steps and in which 10 up-setting operations for building up stock at the tension rod seat and lever pivot pin holes is obviated.

These and other objects are accomplished by means of the method disclosed on the accompanying sheets of drawings in which—

15 Figure 1 is a fragmentary top plan view and—

Figure 2 is a fragmentary side view of a rolled bar of stock from which a blank is to be cut for the formation of a fulcrum.

20 Figure 3 is an enlarged top plan view and—

Figure 4 is a side elevation of a blank cut from a bar, such as shown in Figures 1 and 2, said blank having its ends reduced in 25 width for the formation of feet to be secured to the compressed member of the brake beam.

Figure 5 is a top plan view and

30 Figure 6 is a front view on a still larger scale of the blank after it has been bent intermediate its ends to form spaced legs with a closed end and the legs adjacent the closed ends pinched laterally inwardly and the end provided with a groove to start the formation of the tension rod seat.

Figure 7 is a top plan view, and

Figure 8 is a front view after the body 40 of the fulcrum has been twisted through the usual angle of 40° for use in connection with an inclined brake lever.

Figure 9 is a top plan view, and

Figure 10 is a front view of the fulcrum after the forging operation and the tension rod seat is completely formed.

45 Figure 11 is a top plan view, and

Figure 12 is a front view of the fulcrum after the flashing has been removed.

Figure 13 is a top plan view, and

50 Figure 14 is a front elevation of the completed fulcrum, the lever pivot pin holes having been provided and also the holes in the feet for attachment to the compression member.

Figure 15 is a top plan view of a bulldozer

in which in a single operation the blank is 55 bent, the legs at the closed end pinched inwardly and the closed end provided with a groove in the formation of a tension rod seat.

Figures 16, 17 and 18 are perspective views of die members used in the operation 60 of forging the tension rod seat after the fulcrum blank has been operated upon in the bulldozer.

The various novel features of the invention will be apparent from the following description and drawings, and will be particularly pointed out in the appended claims.

Referring to the figures of the drawings, it will be noted that in Figures 1 and 2 there is shown a fragmentary view of a continuous bar 10 having elongated bosses 11 and that blanks such as shown in Figures 3 and 4 may be cut from said continuous bar for the formation of brake beam fulcrums.

In Figures 3 and 4 the blank is shown as 75 having the enlarged central elongated portion or boss 11 and also as having relatively thin ends 12. The elongated boss 11 is provided to secure sufficient stock to obviate the necessity for up-setting the blank at the 80 point where the tension rod seat is formed and at the points where the lever pivot pin holes are formed, it being understood that an increased amount of stock is required to give sufficient body and strength to the tension rod seat and to give sufficient bearing area for the pin forming the connection between the brake lever and fulcrum. Also in Figures 3 and 4, it will be noted that the 85 ends of the blank after being heated have 90 been reduced in width to provide feet 13, which form means for attaching the fulcrum to the compression member of a brake beam. The heated blank as shown in Figures 3 and 4 is placed upon supports 14 in 95 the bulldozing machine as indicated by dotted lines at 15 in Figure 15. The bulldozer is provided with two oppositely arranged arms 16 pivotally mounted at two space 100 points 17 and at their outer ends are provided with rollers 18 which are caused to travel in cam races 19 for moving the arms inwardly toward each other for bending the blank to form spaced legs with a closed end around the mandrel 20. During this operation, it will be appreciated that the bed 21 with the mandrel 20 is caused to move longitudinally with respect to the arms 16 in co-

operating to bend the bar as described. It will be noted that the mandrel has a reduced end portion 22 which cooperates with shoulders 23 on the arms 16 for pinching the spaced fulcrum legs 24 laterally inwardly at the closed end of the fulcrum to stiffen the stock to resist lateral bending at such point while end pressure is applied and before the cavity 30 and cavity 36 in dies, 10 shown in Figures 16, 17, and 18 are filled in giving the tension rod seat its final shape. At the same time that the legs 24 at the closed end of the fulcrum are pinched inwardly, a groove 25 is formed in the bent 15 end of the fulcrum by a ridge 26 formed in the recessed head of the member 27 in the bulldozer which cooperates with the mandrel 20. The fulcrum blank after thus being treated in the bulldozer appears as in 20 Figures 5 and 6.

The main body portion of the fulcrum is then twisted through an angle of 40° as indicated in Figures 7 and 8, whereupon legs 24 of the fulcrum are placed in a position 25 to be received by the grooves 26 in the die members 27, said grooves being spaced by supporting portions 28. Cooperating with the die members 27 is another die member 29, which is slidably received in the recess 30 of the die members 27. In connection with giving the tension rod seat its final shape, it will be noted that the die member 29 has a recess 36 with a ridge or 35 projection 31 which conforms to the shape of the final seat portion 32 at the tension rod end of the fulcrum as shown in Figures 9 and 10. As a result of experimentation it has been found that unless the legs 24 are offset laterally as at 37 to stiffen the legs 40 at such point, said legs at such point will bend as the die 29 moves inwardly within the cavity 30 before the die opening 36 is properly filled. It will be understood that during a progressive movement of the die member 29 within the recess 30 of the then 45 closed die members 27, the tension rod seat is formed. During this operation in some instances a flashing 33 is formed from excess metal. This flashing is then removed leaving the fulcrum as shown in Figures 11 and 12 and whereupon the lever pivot pin holes 34 are drilled and openings 35 are punched in the feet 13 for the reception of attaching rivets as shown in Figures 13 and 14.

55 By means of this simple and practical method a brake beam fulcrum is formed to meet all of the requirements under service conditions.

It is my intention to cover all of the modifications of this invention falling within the spirit and scope of the following claims.

I claim:

1. The method of making a brake beam fulcrum consisting in providing a heated blank, bending said blank intermediate its

ends to form spaced legs with a closed end and pinching said legs laterally inwardly at the closed end to stiffen the stock sufficiently to resist lateral bending at such point occasioned by pressure applied during the final shaping of the tension rod seat, and then forging said closed end to give the tension rod seat final shape. 70

2. The method of forming the tension rod seat of a brake beam fulcrum consisting in providing a heated blank, bending said blank intermediate its ends to form spaced legs with a closed end, pinching said legs inwardly at the closed end to stiffen the stock sufficiently to resist lateral bending at such point occasioned during subsequent treatment, and then treating said closed end to give the tension rod seat final shape. 75

3. The method of forming the tension rod seat of a brake beam fulcrum consisting in providing a heated blank, bending said blank intermediate its ends to form spaced legs with a closed end, forcing said legs laterally at the closed end to stiffen the stock sufficiently at such point to resist bending under pressure subjected in another direction occasioned by subsequent treatment, and then treating said closed end to give the tension rod seat final shape. 80 90

4. The method of forming the tension rod seat of a brake beam fulcrum consisting in providing metal constituting spaced legs of the fulcrum proper, offsetting the tension rod end of said legs with respect to the balance of said legs to stiffen said legs against bending due to end pressure occasioned by subsequent treatment, and then shaping the connected offset ends of said legs to give the tension rod seat final form. 95 100

5. The method of forming the tension rod seat of a fulcrum consisting in providing a blank having a central enlargement, bending said blank at said central enlargement for providing sufficient stock to form a tension rod seat without upsetting the metal for such point, then offsetting the metal directly adjacent the bend to stiffen same against bending by end pressure occasioned by subsequent treatment, and then subjecting said bent end to end pressure to give the tension seat final shape. 105 110 115

6. The method of forming a brake beam fulcrum consisting in providing a blank having an elongated central enlargement for providing sufficient metal for a tension rod seat and lever pivot pin bearings of adequate area without upsetting the metal at such points, bending said blank at an intermediate point to form spaced legs with a closed end, pinching said legs laterally inwardly at the closed end to stiffen the stock sufficiently at said point to resist bending thereof before the die is filled and upsetting takes place in the final shaping of the tension rod seat, then subjecting said closed end to pressure 120 125 130

to give the tension rod seat final shape, and then providing said legs with lever pivot pin holes.

7. The method of making a brake beam fulcrum consisting in providing a heated blank, bending said blank intermediate its ends to form spaced legs with a closed end and pinching the legs laterally inwardly at the closed end to stiffen the stock to resist lateral bending at such point occasioned by pressure applied in the final shaping of the tension rod seat, and then providing said closed end with a groove for forming a tension rod seat.
- 15 8. The method of making a brake beam fulcrum consisting in providing a heated blank, bending said blank intermediate its ends to form spaced legs with a closed end, grooving said closed end for forming a tension rod seat, and pinching said legs laterally inwardly at the closed end to stiffen

same against bending during the subsequent treatment, and then giving the tension rod seat final shape.

9. The method of forming a tension rod seat in a brake beam fulcrum consisting in providing a heated blank and in a single operation bending the blank intermediate its ends to form spaced legs with a closed end, grooving said closed end to start the formation of a tension rod seat, and pinching said legs laterally inwardly at the closed end to stiffen the stock at such point sufficiently to resist bending before the die is filled and upsetting takes place in the final shaping of the tension rod seat and then finally shaping the closed end to form the tension rod seat.

Signed at Hammond, Indiana, this 7th day of October, 1924.

LOREN L. WHITNEY.
